GRANDON E. ECKERT, OF EAST LIVERPOOL, OHIO, ASSIGNOR TO THE R. THOMAS & SONS CO., OF EAST LIVERPOOL, OHIO, A CORPORATION OF OHIO.

INSULATOR FITTING.

Application filed December 28, 1920. Serial No. 433,565.

My invention relates to insulator fittings, and particularly to a terminal fitting connecting the legs of the insulator link and the suspension device by which a string of insulators of the Hewlett or like type, is either on the one hand supported from a suitable carrier, or on the other hand supports a cable. The particular object of my invention is to provide a terminal fitting with which mechanical connection can be readily made to the heads of the link and suspension device without the use of clamping bolts or the like, the fitting being provided with appropriate means movable into and out of position to free or to lock the connection so made.

In the accompanying drawings—

Fig. 1 is a side elevation of a fitting in which my invention is embodied in one form, showing cooperating elements associated therewith;

Fig. 2 is a broken inverted plan thereof; and

Figs. 3 and 4 are respectively sections on the lines 3—3 and 4—4, Fig. 1.

Referring to the drawings, the invention is here embodied in a one-piece, hollow casting 5 of elongated ellipsoidal shape in plan and slight depth compared to the length.

Adjacent opposite ends of the casting are lateral entry gates 6 and 7 opening to the interior of the casting through one side wall thereof, and having associated channels 8 which extend through the lower or inner (toward the insulator) wall of the fitting to the longitudinal axis thereof. Inasmuch as the entry openings 6 and 7 are formed above the level of the bottom or inner wall of the casting, and are of greater width than the channels 8, the portions 9 of the side wall below the entry apertures or gates 6 and 7 form retaining lips which engage the heads 10 of the link 11 and prevent their lateral escape when socketed in the fitting with their shanks lying in the channels 8.

A similar entry aperture 12 spaced between the gates 6 and 7 is opened through the same lateral wall of the fitting, but with its associated channel 13 extending through the top or outer (away from the insulator) wall thereof. This aperture 12 is spaced downward from the top wall of the fitting and the portions 14 of the side wall bounding the channel 13 form a stop preventing the lateral escape of the head 15 of the sus-

pension device 16 when socketed in the fitting with its shank lying in the channel 13.

Opening through the side wall of the fitting opposite that of the entry gates 6, 7 and 12 are holes 17, 18 and 19 lying in substantially the same horizontal plane and accommodating the spring cotters 20. The holes 17 and 18 opposite end gates 6 and 7 for the link heads, are located adjacent the top or outer wall of the fitting, while the hole 19 for the head of the suspension device opens adjacent the bottom or inner wall of the fitting—that is to say, in each case adjacent the wall opposite that from which the retaining lips 9 and 14, respectively, rise. Consequently, since the width of the cotter pins is predetermined with respect to the thickness of the heads 10 and 15, they serve, when inserted, to block the escape of these heads from their lateral entry gates by holding the heads in the plane of the retaining lips 9 and 14. These cotter pins are preferably of the type shown in my co-pending application Ser. No. 413,855, filed September 30, 1920, and patented June 12, 1923, No. 1,458,811 and have heads 21 preventing their complete insertion through the holes 17, 18 and 19, integral spring legs having offset feet 22, preventing accidental complete withdrawal, and intermediate outwardly bowed points 23 forming shoulders which co-operate with the heads 21 to hold the cotters in inserted obstructing position.

As here shown, the entry apertures or gates 6, 7 and 12 all open through the same side wall of the fitting, and the cotter holes through the opposite side walls. This construction facilitates assembly as well as manufacture, and has the advantage that the lineman is not apt to forget to push in any of the cotters after assembling the link and suspension devices, since all of the cotters project from the same side of the fitting. It is of course understood that the cotters are shifted in their holes to move them out of obstructing position during assembly of the parts, and after the heads are socketed in the fitting the cotters are then pressed inward again to the obstructing position indicated in the drawing. Although the cotters are of spring metal they are positioned edgewise with respect to the heads, and thus form rigid stops.

Inasmuch as the link 11 is as short as possible, and therefore holds the insulator

24 close to the fitting, the bottom or inner wall of the latter is preferably arched, as at 25, to accommodate the hub 26 of the insulator during the assembly of the link 5 heads with the fitting. The upper or outer wall of the fitting follows the general curvature of the inner wall, but its rise from the straight end portions is slightly accentuated to afford a flat 27 against which the head 15 9 of the suspension device is seated. This slightly arched construction has the effect, furthermore, of strengthening the fitting in the mid-area, which is engaged by the suspension device.

15 The construction as a whole is extremely simple, and presents the advantages not only of economy in manufacture and simplicity of attachment, but also of eliminating the necessity for clamping bolts and nuts, which 20 are apt to become loose or lost. Inasmuch as the spring cotters are carried by the fitting at all times, the lineman is relieved of the necessity of supplying himself with supplemental fastening devices, or, at most, he 25 need carry but a few spring cotters in his pocket to replace any that may be found broken or lost. The construction has the further advantage that when the cotter pin is drawn out of obstructing position in order 30 to make or break connection between the associated parts and the fitting, its projecting position serves as a reminder to the lineman to press it inward to locking position.

As shown, the fitting is hollow. It would 35 of course be a simple matter to reinforce it by arranging tie webs connecting the inner and outer walls between the gates 6, 7 and 12, if additional strength were demanded of the fitting. Various other modifications of 40 detail construction will readily occur to those dealing with this fitting without departing from what I claim as my invention, the underlying thought of which is a one-piece structure provided with laterally open walls 45 with channels extending respectively toward

and away from the insulator to receive the heads and shanks of a link and suspension device, together with appropriate means such as spring cotters permanently associated with the fitting and adapted to be moved 50 into and out of obstructing position in the several walls for the purpose set forth.

I claim—

A terminal fitting for link-type insulators, said fitting comprising a hollow casting affording an interior chamber bounded by spaced side walls and spaced top and bottom walls, the bottom wall being concaved and the top wall being arched, and the side walls converging toward opposite ends of the casting, the bottom wall of the chamber adjacent its opposite ends being shaped to afford interior seats for the anchor heads of an associated U-link, and the top wall being shaped at an intermediate point to afford an intermediate point to 65 an interior seat for the anchor head of a suspension device, one of the side walls of the fitting being apertured to afford three T-slot gates, two of which extend through the bottom wall of the chamber to accommodate the shanks of the U-link when its anchor heads rest in the seats in said bottom wall, and one of which extends through the top wall of the fitting to accommodate the shank of the suspension device when its 70 anchor head rests in the intermediate seat, the opposite side wall of the fitting being apertured adjacent the top wall of the fitting at opposite ends thereof and substantially in register with said T-slot gates, and also being apertured adjacent the bottom wall of the fitting at a point substantially in register with the intermediate T-slot gate, said apertures serving to accommodate filler pins which prevent the inserted anchor heads 75 from escaping through the T-slot gates of the fitting.

In testimony whereof I have signed by name to this specification.

GRANDON E. ECKERT.
